United States Patent Office

Des. 193,986
Patented Nov. 6, 1962

193,986

FOUNDATION GARMENT

Seraphina C. La Bue, New York, N.Y., assignor to Vanity Fair Mills, Inc., Reading, Pa., a corporation of Pennsylvania

Filed Apr. 17, 1962, Ser. No. 69,749

Term of patent 14 years

(Cl. D20—2)

FIG. 1

FIG. 2

FIG. 1 is a front elevational view of a foundation garment showing my new design; and

FIG. 2 is a rear elevational thereof.

I claim:

The ornamental design for a foundation garment, substantially as shown.
